T. W. SAUL,
HAIR FASTENER,
FILED MAY 4, 1921.

INVENTOR:

T.W. Saul

by
Pierre Barnes
ATTORNEY

UNITED STATES PATENT OFFICE.

TOM W. SAUL, OF SEATTLE, WASHINGTON.

HAIR FASTENER.

Application filed May 4, 1921. Serial No. 466,645.

To all whom it may concern:

Be it known that I, TOM W. SAUL, a citizen of the United States, residing at Seattle, in the county of King and State of Washington, have invented certain new and useful Improvements in Hair Fasteners, of which the following is a specification.

This invention relates to hair pins and other articles of a similar character.

10 The object of my improvements is to provide a fastener which will more effectually serve to secure the strands of a woman's hair into a self sustaining mass.

Another object is to provide a hair fastener which may be readily applied to or withdrawn from the hair and maintain the strands or portions thereof in exact predetermined positions.

Another object is to provide a hair fastener having its leg or prong element formed to engage the hair and in turn, be engaged thereby in a manner to prevent the fastener being accidentally displaced or lost.

Other objects and advantages of the invention will appear from the following description.

The invention consists, essentially, in a hair fastener having leg or prong members which are bent or formed in a novel manner to afford complementary projecting and recessed portions as will be hereinafter described and claimed.

In the accompanying drawings,—

Figure 1 is a front elevation of a hair pin embodying the present invention; and Fig. 2 is a similar view illustrating my invention applied to a woman's back-comb.

Referring to the drawings, the hair pin shown in Fig. 1 comprises two leg members 5 and 6 connected by the usual loop 7.

Intermediate its length and between straight portions 8 and 9 of the leg 5, the latter is formed with two inwardly directed bends 10 and 10¹ and an outwardly directed bend 11, said bends constituting a shape substantially similar to the letter W.

The other leg 6 is formed between straight portions 12 and 13 thereof with an inwardly directed bend 14 which is arranged to ex-

tend into the inner recess 15 obtaining between the bends 10 and 10¹ of the leg 5.

The axis of said bends are substantially perpendicular to the straight portions of the respective legs, and the axis of the bend 14 is located medially of the bends 10 and 10¹.

The above described arrangement of the bends provides an indentation or bay 16 in the outer side of the leg 6 and between two bays 17 and 17¹ in the outer side of the leg 5.

The operation of a hair pin embodying the above described features may be explained as follows:

In dressing a woman's hair she engages a strand in the loop 7 of the pin and pushes the latter into the relatively compact inner portion of her hair. When the pin is fully inserted, the bend portions of the respective legs engage in such compact body of hair, and portions of the compact which were directed by the prong portions 9 and 13 of the pin enter into the bays 16 and 17, 17¹ and exercise pressure against the respective bends as indicated by arrows A and B to produce interlocking engagement between the hair and the pin which will prevent the pin being removed except by a direct pull to displace the wads of hair, so to speak, which are lodged within said bays.

It is to be noted that the pressures due to the resilience of the bodies of compressed hair occupying the bays 17, 17¹, act against the pin in a general direction, see arrows B, to that of the intermediate pressure denoted by arrow A acting in the opposite direction in the bay 16; and furthermore by arranging the bay 16 midway between the bays 17, 17¹ the side pressures are balanced to obviate any tilting or lateral disarrangement of the pin.

In Fig. 2 I illustrate the invention embodied in a comb, conventionally known as a back or side comb. In such an application the outer pair of legs or teeth 5¹, 6¹ depending from the comb stock 18 at each side of the central teeth 19 are similar to the legs of the hair pin above described and the various characteristic elements or features of the teeth 5¹, 6¹ are denoted by reference num-

bers employed to designate corresponding features of the hair pin. The function of the teeth 5¹ and 6¹ of the comb being similar to the hair pin legs will, it is thought, be understood without further explanation.

What I claim, is,—

A hair fastener having a leg formed at approximately its midlength with a portion of substantially W-shape, and a second leg 10 formed at approximately its midlength with

a portion of substantially V-shape which extends into the central recess of the W-shaped portion of the first named leg.

Signed at Seattle, Washington, this 28th day of April 1921.

TOM W. SAUL.
